Edgar M. Kitchin,
his Attorney.

UNITED STATES PATENT OFFICE.

SAMUEL T. WHITAKER, OF COLUMBUS, GEORGIA, ASSIGNOR OF FIFTY-ONE ONE-HUNDREDTHS TO RALPH B. SMALL, OF COLUMBUS, GEORGIA.

CAP-REMOVER.

1,267,154.

Specification of Letters Patent. Patented May 21, 1918.

Application filed August 24, 1916. Serial No. 116,633.

To all whom it may concern:

Be it known that I, SAMUEL T. WHITAKER, a citizen of the United States, residing at Columbus, in the county of Muscogee and 5 State of Georgia, have invented certain new and useful Improvements in Cap-Removers; and I do hereby declare the following to be a full, clear, and exact description of the invention, such as will enable others skilled 10 in the art to which it appertains to make and use the same.

This invention relates to improvements in that type of cap removers adapted especially for removing crimped caps from bottles.

15 The object in view is the production of a light, simple, efficient and inexpensive structure of minimum size.

With this and further objects in view, the invention comprises certain novel features 20 of construction, combinations and arrangements of parts as will be hereinafter specified and claimed.

In the accompanying drawing,

25 Figure 1 is a perspective view of a bottle cap remover embodying the features of the present invention and illustrated as applied in operative relation to a crimped cap to be removed.

Fig. 2 is a view in side elevation of the 30 neck of a bottle with an embodiment of the invention attached thereto as indicating one manner of supplying cap removers to the market.

Fig. 3 is an inverted plan view on an enlarged scale of the cap remover seen in 35 Fig. 1.

Fig. 4 is a vertical section taken on the plane indicated by line 4—4 of Fig. 3.

Referring to the drawing by numerals, 1 40 is a flat oblong body of sheet metal terminating in a downwardly-turned tab 2 at one end and a downwardly-turned beak 3 at the other end. Out of the body 1 is stamped a tongue 4 which is turned at its free end to 45 form a hook 5. The beak 3 is stamped V-shaped with the apex of the V forming the point of the beak.

In operation, the instrument is applied, 50 as seen in Fig. 1, with the hook 5 engaging beneath the edge of the crimped cap and with the beak 3 engaging the upper surface

of the cap, the tab or end grip portion 2 outstanding from the cap. The tab is gripped and the outer end of the instrument is elevated, which results in the lifting of 55 the cap from the bottle.

One efficient method of use of this instrument in practice consists in placing the finger in the angle formed between the body 1 and tab 2 so as to be beneath the instrument, and by placing the thumb on top of the body 1 the tab 2 serves as an effective gripping portion conforming generally to the shape of the finger. Owing to the fact that the finger will fit between the rear edge 60 of the tongue 4 and the tab 2 while resting against the under surface of the body 1 enables the operator to get a very effective and firm grip on the instrument, which assures 65 satisfactory operation thereof, such as would 70 not be obtainable with a like instrument provided with a straight body and having no curved tab. The beak 3 usually forms a dent on the upper surface of the cap and thus assures against slipping of the instrument 75 during operation.

The instrument, of course, may be distributed on the market in packages or otherwise as desired, and I find one effective means of distribution consists in securing 80 the instrument in any appropriate manner to the neck of a bottle closed by a crimped cap. The structure described is not only effective in its operation as above described, but is so designed and constructed as to be susceptible 85 of production at such a low rate as to be practicable for distribution with each bottle of any particular substance without necessitating an additional charge for the bottle.

90 What I claim is:

1. A crimped cap remover comprising a body formed of a flat strip of metal bent at one end to form a downwardly-turned tab and bent and tapered at the other end 95 to provide a point, a portion of the material of the body being stamped to form an outstanding hook adapted to engage beneath the flange of a crimped cap when the point engages the upper surface of the cap.

100 2. A crimped cap remover comprising a body formed of a flat strip of metal later-

ally bent and terminated at one end to form a point adapted to dent the upper surface of a crimped cap, a portion of the body portion being stamped and bent to outstand 5 from the body portion and formed into a hook adapted to engage the lower edge of the flange of such cap.

In testimony whereof I affix my signature in presence of two witnesses.

SAMUEL T. WHITAKER.

Witnesses:

H. C. McCUTCHEON,
T. L. BOWDEN.
